UNITED STATES PATENT OFFICE.

HANS LUTZ, OF ELMIRA, NEW YORK, ASSIGNOR TO THE WILLYS-OVERLAND COMPANY, OF TOLEDO, OHIO, A CORPORATION OF OHIO.

GRINDING MACHINE.

Application filed October 27, 1919. Serial No. 333,766.

My invention relates to a grinding machine and has for its object to provide more particularly an improved machine for grinding or finishing ball bearing races and the like, although the machine may be used for various other purposes if desired.

A further object of the invention is to provide an improved work holder capable of accommodating various sized work pieces without changing or affecting adjustment of the holder.

Another object of the invention is to provide an improved mounting for a shaft adapted to support a tool in position to engage a work piece carried by a work holder mounted opposite thereto, the shaft being mounted in such a manner as to prevent flexing thereof during operation which might cause the tool carried thereby to change its position or vibrate upon the work piece.

Another object of the invention is to provide improved means for oscillating a work holder carrying a work piece in position to be engaged by a suitable tool during the oscillatory movement of the holder.

Another object of the invention is to provide a relatively fixed rotatable grinder in combination with an oscillatory work holder adapted to be simultaneously oscillated and rotated upon which may be supported a ball race or similar work piece in such a manner as to grind a curvilinear groove upon the work piece.

To these and other ends the invention comprises certain novel features of construction and arrangement of parts as will be hereinafter more fully pointed out and claimed, it being understood that the invention is susceptible to various modifications without departing from the spirit of the invention as comprehended by the claims appended hereunto.

A structure constituting one embodiment of my invention is illustrated in the accompanying drawings forming a part of this specification in which:

Figure I is a plan view of a machine embodying the invention.

Figure II is an end elevation of the same.

Figure III is a sectional elevation taken on lines III—III of Figure II.

Figure IV is an enlarged sectional plan taken on lines IV—IV of Figure III.

Figure V is a transverse section taken on lines V—V of Figures III and IV. 55

Figure VI is an enlarged fragmentary sectional plan through the work holder with the grinding tool shown in engagement with the curvilinear groove of a ball bearing race, the extreme position of the work holder being indicated in one case by full lines and in the other by dotted lines. 60

Figure VII is a fragmentary end elevation of a portion of the means for effecting the oscillation of the work holder. 65

Figure VIII is a sectional elevation taken on line VIII—VIII of Figure VII and also of Figure IX.

Figure IX is a sectional plan taken on line IX—IX of Figures III and VII. 70

Figure X is a sectional elevation taken on line X—X of Figure IX.

Figure XI is a sectional elevation taken on line XI—XI of Figure IX.

Figure XII is an enlarged sectional elevation taken on line XII—XII of Figure III, and 75

Figure XIII is a fragmentary sectional plan taken on line XIII—XIII of Figure III. 80

Like reference characters refer to similar parts throughout the several views of the drawing.

In the present invention I have designed a machine which is particularly adapted for holding and oscillating a work piece, such as a ball bearing race, which is both rotated and oscillated simultaneously, with an improved mounting for a grinding tool adapted to be rotated in engagement with the race to form therein the ball bearing groove, the grinding tool being relatively fixed with respect to the work holder and being mounted in such a way that it may be rotated without vibration in order that a more perfect seat for the ball may be formed within the race. 85 90 95

While the invention is particularly adapted for grinding ball bearing races, it will be understood that any suitable tool may be used in place of a grinder and that work pieces of various kinds may be operated upon and further that the machine may be used as a lathe if desired by discontinuing the operation of the mechanism provided for effecting oscillation of the work holder. 100 105

cillation of the carriage and the work holder thereon, the slide 12 is preferably provided with a downwardly extending sleeve or bearing 64 projecting through and movable in a longitudinal slot 65 in the bed 11 of the base 10 as shown in Figures III and XIII. A shaft 66 for actuating the work supporting carriage is journaled in the bearing 64 and is keyed upon the turn-table 16 as indicated at 67 in Figure III. The shaft 66 is held against longitudinal displacement upon the bearing 64 by means of a nut 68, and the lock nuts 69 upon the threaded portion 70 of said shaft. A bracket 71 is supported beneath the bed 11, preferably upon the bearing sleeve 64 of the slide 12 which bracket carries at its upper end a sleeve 72 surrounding the bearing sleeve 64 with which it is rigidly connected in any suitable manner such as set screw 64^A. The bracket 71 is provided with a depending portion 73 upon which is mounted in suitable ways a slide 74 having at its ends transversely extending lugs 75 arranged to slide upon the vertically disposed plate portion 76 of the brackets as indicated in Figures VII and IX. The shaft 66 is provided at its lower end with a reduced portion 77 adapted to receive a disc 78 at a point opposite the slide 74 as indicated in Figure III. The disc 78 is provided at one side with a recess in which is disposed the outer ends of the upper and lower steel tapes 79 shown in Figure XI, and likewise the intermediate tape 80, all of which are clamped upon the disc by means of the block 81 held upon the disc by the screws 82 as shown in Figures IX and VII. The opposite ends of the tapes 79 are connected with a head 83 as indicated at 84 in Figure XI, said head being adjustable in a recess 85 in one of the lugs 75 of the slide 73, the adjustment being effected by means of a threaded extension 86 extending through said lug and provided on the outside thereof with the nuts 87. The intermediate tape 80 has its inner end anchored in a slotted head 88 by means of the bolts or rivets 89 as indicated in Figures IX and XI, said head being adjustable in a recess 90 in the lug 75 at the right hand side of the bracket, the adjustment being effected by means of the threaded extension 91 on the head extending through said lug and secured by means of the nuts 92. The adjustable heads 83 and 88 are provided for the purpose of properly tensioning the steel tapes connected therewith which are wound in opposite directions upon the disc 78. The central portion of the plate 76 of the bracket 71 is cut away as indicated at 93 to permit the disc 78 to be brought into close proximity to the slide 74 as indicated in Figure III. The slide 74 is provided on the opposite sides of its center with the longitudinally extending slots 94 in which are mount- ed blocks 95 having heads 96 movable in the groove 97 formed in the slide as indicated in Figures IX and X. The blocks 95 are adjustable in the slots 94 by means of the screws 98 extending through the lugs 75 of the slide as indicated in Figure IX. A shaft 99 is screwed into each of the lugs 95, said shaft being provided with rollers 100 secured by washers 101 which are held against displacement by means of the cotter pins 102 extending through the outer ends of the shafts. Mounted between the rollers and in engagement therewith is a heart-shaped cam 103 carried on the inner end of the shaft 104 journaled in a bearing 105 supported by the vertically disposed ribs 106 of the bracket 71 as shown in Figures III and XII. The outer end of the shaft 104 is provided with a sprocket 107 carrying a chain 108 connected with a smaller sprocket 109 on a shaft 110 journaled in bearings 111 carried by the extension 43 of the base 10 as indicated in Figure III. The shaft 110 is provided at its outer end with a pulley 112 adapted to be driven by a belt 113 connected with any suitable source of power. The chain or flexible connection 108 between the sprockets 107 and 109 permits of the shifting of the bracket 71 within certain limits when the slide 12 is moved upon the bed 11 from one position to another. It will be seen from Figure III that separate and independent means have been provided for operating the work holder and the tool holder and for oscillating the carriage upon which the work holder is mounted, but it will be understood that if desired the tool holding shaft may be driven by the same means provided for effecting rotation of the shaft 104. It will be obvious that instead of driving the shaft 104 by means of a sprocket chain, said shaft may be readily driven by means of suitable gears mounted in any desired manner upon the machine.

In the operation of my improved machine, the work piece is first secured in the chuck 29 after which longitudinal adjustment of the standard 18 is effected to bring the work piece at the desired point opposite the tool 37. The work holder is then shifted laterally of the tool until the work is brought into engagement therewith by moving the slide 17 the desired amount upon the table 16. After the standard and slide 17 have each been clamped in their proper position of adjustment so that the tool will engage the work piece at the desired point, rotation of the pulleys 27 and 48 is then effected by means of the belts 28 and 49 respectively. At the same time the shaft 110 is rotated by means of the pulley 112 and belt 113, thereby effecting rotation of the shaft 104 through the flexible connection 108. Rotation of the shaft 104 effects rotation of the cam 103 thereon and by rotation of the cam recipro-

cation of the slide 74 is effected by reason of the rotation of the cam in contact with the rollers 100 supported by said slide. Reciprocation of the slide by means of the cam effects oscillation of the disc 78 by means of the steel tapes interposed between the disc and said slide. The disc 78 being rigidly connected with the shaft 66 effects oscillation of the same, whereby the turn-table 16 10 on the circular track 15 and the parts superimposed upon the table are also oscillated. The work holder is therefore both rotated and oscillated at the same time that the tool is being rotated in contact with the work. 15 The work holder is preferably oscillated through an angle of 90 degrees as indicated in Figure VI. The oscillation of the work holder is particularly advantageous in cases where it is desired to grind a curvilinear 20 groove in the work piece as in the case of a ball bearing race such as is indicated in Figure VI. This method may also be employed in grinding or producing grooves in other forms of work, and by using the 25 proper chuck, the grinding tool may be made to operate either interiorly or exteriorly of the work.

While I have used the term "grinder" in the claims and specification, it will be understood that I do not employ it in a limited sense, since any suitable tool may be used according to the character of the work to be performed.

What I claim as new and desire to secure 30 by Letters Patent is:—

1. In a machine of the class described, the combination of a base, an adjustable slide upon said base having a circular track thereon, means for locking said slide in different 40 positions of adjustment, a carriage mounted for oscillation upon said track, a work holder upon said carriage, a shaft journaled upon said slide and connected with said carriage, a bracket connected with said track, a second slide reciprocably mounted upon said bracket, means for reciprocating the same, and means connecting said shaft with said second slide whereby, when the latter is reciprocated, oscillation of said shaft and said carriage will be effected.

2. In a machine of the class described, the combination of a base, a circular track adjustable thereon, means for locking said track in different positions of adjustment, a carriage mounted for oscillation upon said track, a work holder upon said carriage, a shaft journaled upon said track and connected with said carriage, a bracket connected with said track, a slide reciprocably mounted upon said bracket, means for reciprocating the same, means connecting said shaft with said slide whereby when the latter is reciprocated oscillation of said shaft and said carriage will be effected, and a tool holder adapted to support a tool in engage-

ment with a work piece carried by said work holder during oscillation of the same.

3. In a machine of the class described, the combination of a base, a circular track adjustable thereon, means for locking said track in different positions of adjustment, a carriage mounted for oscillation upon said track, a work holder upon said carriage, a shaft journaled upon said track and connected with said carriage, a bracket connected with said track, a slide reciprocably mounted upon said bracket, a shaft journaled in the bracket, a cam upon said shaft operatively connected with said slide for reciprocating the same, means interposed between said slide and the first mentioned shaft for oscillating the latter to effect oscillation of said carriage and the work holder thereon, means for actuating the second mentioned shaft, and a rotatable tool holder adapted to support a tool in engagement with the work piece carried by said work holder during oscillation of the same.

4. In a machine of the class described, the combination of a base, a circular track adjustable thereon and having a sleeve at one side thereof, a shaft journaled in said sleeve, a carriage upon said track connected with said shaft, a work holder upon said carriage, a bracket having an annular portion engaging said sleeve, a slide upon said bracket, means interposed between said slide and said shaft for oscillating the latter upon reciprocation of the slide, a shaft journaled in said bracket, means actuated by said last mentioned shaft for reciprocating said slide, means serving to effect operation of the second mentioned shaft in any position of adjustment of said track, and a tool holder adapted to support a tool in engagement with a work piece carried by said work holder during oscillation of the same.

5. In a machine of the class described, the combination of a base, a circular track thereon having a sleeve at one side thereof, a carriage upon said track, a work holder upon said carriage, a shaft having one end connected with said carriage and extending through and journaled in said sleeve, a locking member for holding said shaft against longitudinal displacement, a bracket secured upon said sleeve, a slide upon said bracket, a disc upon said shaft, flexible connections between said disc and said slide whereby upon movement of said slide in opposite directions oscillation of said shaft will be effected, spaced rollers connected with said slide, a second shaft carried by said bracket, a cam connected with said second mentioned shaft and extending between and in engagement with said rollers, means for actuating the second mentioned shaft, and means for supporting a tool opposite said work holder.

6. In a machine of the class described, the

combination of a base, a circular track thereon, a carriage mounted for oscillation upon said track and having a sleeve at one side thereof, a work holder upon said carriage, a shaft journaled in said sleeve having one end connected with said carriage and the other end projecting beyond the sleeve, means for preventing longitudinal displacement of said shaft, a disc secured upon the projecting end of said shaft, a bracket connected with said sleeve, a slide upon said bracket, flexible members wound in opposite directions upon said disc, means for adjustably connecting the outer ends of said flexible members with said slide, spaced rollers adjustably mounted upon said slide, a cam mounted between said rollers, means for rotating said cam, and means for supporting a tool in position to engage a work piece carried by said holder.

7. In a machine of the class described, the combination of a base, a circular track thereon, a carriage upon said track, a work holder upon said carriage, a shaft journaled upon said track and operatively connected with said carriage, a bracket carried by the track, a slide upon said bracket, adjustable flexible

connections between said slide and said shaft whereby when the slide is reciprocated oscillation of said shaft will be effected, means for reciprocating said slide, and means for supporting a tool in position to engage a work piece carried by said holder.

8. In a machine of the class described, the combination of a base, a circular track thereon, a carriage upon said track, a work holder upon said carriage, a shaft operatively connected with said carriage and journaled in a bearing upon said track, a bracket mounted adjacent said carriage, a slide mounted upon said bracket, flexible connections between said slide and said shaft for oscillating the latter upon reciprocation of the slide, adjustable blocks mounted in recesses formed in said slide, rollers carried by said blocks, a cam mounted between said rollers, means for actuating said cam to effect reciprocation of said slide, and means for supporting a tool in position to engage a work piece carried by said holder during oscillation of said carriage.

In testimony whereof, I affix my signature.
